BOW-TIE CLASP

Edouard Firon and André Firon, Paris, France

Application May 10, 1939, Serial No. 272,848
In France May 11, 1938

4 Claims. (Cl. 24—81)

Our present invention relates to clips or clasps for mounting bow-ties thereon, and more particularly to bow-tie clips or clasps of the type that may be attached to the front flaps of a fold-over shirt collar to maintain the bow-tie mounted thereon in place upon the collar.

It is an object of this invention to provide clips or clasps of the character described which are adapted to firmly and securely engage the folded over collar flaps of a shirt, to thereby retain the bow-tie thereon firmly and securely in place, thus enhancing the appearance of the wearer.

It is also an object of this invention to provide bow-tie clips or clasps of the character described which are easy and convenient to attach and remove and which may be so attached and removed with a minimum disturbance and disarrangement of the bow-tie fabric mounted thereon, and in which such bow-tie fabric is spontaneously disposed in proper position upon attachment of the clip upon a collar, thereby increasing the durability of the bow-tie and assuring a continuous appearance of proper arrangement of its parts.

It is another object of this invention to provide bow-tie clips or clasps of the character described which are compact and which, when the bow-tie fabric is mounted thereon, will give the resultant assembly an over-all appearance of compactness and neatness.

It is a further object of this invention to provide such bow-tie clips or clasps which may be easily and readily assembled with the bow-tie fabric and upon which such fabric may be firmly durably secured.

It is a still further object of the present invention to provide bow-tie clips or clasps which are of simplified construction, which are durable, and which possess numerous other advantages and superiorities which will hereinafter be set forth and which will become apparent from the illustrative preferred embodiment thereof hereinafter described and shown in the accompanying drawing.

In the drawing:

Fig. 1 is a top plan view of the clip, before assembly with the fabric of the bow-tie; and

Fig. 2 is a side elevational view of such clip, shown with one of its wings clasped on collar flap and the other in open position, before clasp-ing; the bow-tie being shown in broken lines.

Referring more specifically to the accompanying drawing, the clip or clasp comprises a frame member, generally designated as 10, consisting of a central U-shaped portion 12, having a slight-

ly arcuate base portion 13, and sides 14. The sides 14 are reentrantly bent at a point offset from the base 13, to form detent grooves 16, and then bent again to form sideways extending arms 18, which are preferably disposed at a slight angle to a line tangent to the center of the curve of the base 13. Each arm 18 is preferably of an arcuate cross-section, to reinforce the same against bending.

Each arm 18 is further provided, along each of its longitudinal edges, adjacent its free ends, with fabric gripping serrations or teeth 20 for firmly gripping the underside of a collar upon which the clip may be fastened, and at its free end, with a lip 22 to facilitate insertion of the arm end under a collar flap.

A longitudinally extending, inwardly pressed reinforcing rib 24 is provided centrally along the base 13, which rib extends along the adjoining sides 14 and under and past the detent grooves 16 and partly along the arms 18.

An arcuate leaf spring 26 of a curvature substantially corresponding to the curvature of the base 13 is fixed on the said base, on the outer face thereof, preferably by means of ears 28, integral with the side edges of the base, which ears are bent over to clamp the spring 26 on the base. The spring ends 30 are, preferably of reduced width relative the central portion thereof and each extends over and a short distance past the detent grooves 16.

A pair of clasp arms 34 are provided, each of which cooperates with one of the frame arms 18 to clasp between them the flaps of a shirt collar. Each clasp arm 34 is of a length preferably slightly in excess of an arm 18 and is provided adjacent one end with a slot 36 by which the arm is caught by a spring end 30 to be pressed against the corresponding arm 18. The shorter end of clasp arm 34, on one side of slot 36 is of a length slightly in excess of the distance between the bottom of the detent groove 16 and the portion of the spring end 30 immediately overlying it and is bent at an angle to the remainder of said arm, so that when spring end 30 is inserted into slot 36, and the transverse edge of the clamp arm portion 38 is disposed within the groove 16, the end of the spring which is engaged within the slot 36 will tend to press the other end of the clasp arm 34 either against the face of the corresponding frame arm 18 in which position the forward portion of both will be in contact, or in the opposite direction, toward the corresponding side 14 of the groove

16, which side will limit the movement of the clasp arm in that direction.

Each clasp arm 34 may be reinforced by offset side flanges 40 extending along the portion thereof adjacent the slot 36 and by means of a pressed out rib 42 longitudinally disposed adjacent the free end thereof, the foremost end of said pressed out portion being deepened and enlarged to form an enlarged, knob-like projection 44, which is adapted to fit in the arcuate curvature of the frame arm 18 when the two arms are pressed together, to make contact between them along a substantial area to provide, thereby, increased gripping action between them.

The free end of the clasp arm 34 is widened 15 and provided with a plurality of apertures which serve for the passage of stitching which secures the bow-tie fabric, and more specifically, that portion of the fabric constituting the bow-tie wings 46, which is wrapped around the arm 34. It will be understood that only the inner portions of the wing fabric are so sewed to the clasp arms, so that the outer appearance thereof will not be marred. And it may also be observed at this point that the knot portion 48 of the bow-tie, is wrapped around and sewed about the U-shaped central portion 12 of the frame 10.

It will be observed that with the clip or clasp of the present invention the bow-tie wings are permanently secured around the ends of the clasp arms 34 and are always moved therewith when attached to or removed from a shirt collar, and that, consequently, the wings are maintained in proper position and arrangement at all times and always maintain their proper and correct appearance.

It will also be apparent that the clasp arms 34 about which the bow tie wings are arranged, will, when affixed on a collar, press a portion of the tie fabric into contact with the collar fabric, thereby pressing fabric against fabric and obtaining a maximum of friction against its slipping off the collar or becoming displaced or disarranged thereon, and thus tend to keep the bow-tie more securely in place upon the collar.

This completes the description of the preferred embodiment of the bow-tie and clasp of the present invention. It is to be understood, however, that such embodiment is shown and described by way of illustration only, to make the principles and the general structural features of the invention more readily comprehensible, and is not intended in any way to limit the spirit and scope thereof, particularly as set out in the appended claims.

What we claim is:

1. In a clasp of the character described, a frame comprising a pair of arms and a connecting piece for said arms, each of said arms having a transversely formed groove adjacent its juncture with the said connecting piece, a leaf spring fixed on said connecting piece, its ends overhanging the contiguous ends of the said arms, a pair of clasp arms each fulcrumed by an end in one of said grooves and provided with a slot slidably engaging an end of said spring whereby the free end of the clasp arm is pressed against the corresponding frame arm.

2. In a clasp of the character described, a frame comprising a pair of arms and an off-set portion connecting the said arms, each of said arms having a transversely formed groove adjacent its juncture with the said off-set portion, a leaf spring fixed on said off-set portion, its ends overhanging the contiguous ends of the said arms, a pair of clasp arms each fulcrumed by an end in one of said grooves and provided with a slot slidably engaging an end of said spring, whereby the free end of the clasp arm is pressed against the corresponding frame arm.

3. The structure of claim 1 wherein each of the clasp arms is substantially V-shaped, with the apex of the V formed adjacent the pivoted end thereof and with the arms of the V arranged to extend in the direction of the frame arms.

4. The structure of claim 1 wherein the clasp arms are provided with a plurality of stitch-receiving apertures at their free ends.
